UNITED STATES PATENT OFFICE

144,714

DESIGN FOR AN AIRPLANE

Edward H. Heinemann and Leo J. Devlin, Los Angeles, Calif., assignors to Douglas Aircraft Company, Inc., Santa Monica, Calif.

Application May 2, 1945, Serial No. 119,352

Term of patent 7 years

(Cl. D71—1)

To all whom it may concern:

Be it known that we, Edward H. Heinemann and Leo J. Devlin, citizens of the United States and residents of Los Angeles, in the county of Los Angeles and State of California, have invented a new, original, and ornamental Design for an Airplane, of which the following is a specification, reference being had to the accompanying drawings, forming a part thereof:

Figure 1 is a top perspective view of an airplane in flight showing our new design.

Figure 2 is a side elevational view of the subject airplane depicted in Figure 1 with the extended landing gear shown in dotted lines.

Figure 3 is a bottom plan view of the airplane depicted in Figures 1 and 2.

Figure 4 is a front elevational view of the airplane depicted by Figures 1, 2, and 3 with the landing gear thereof being shown in the extended position by dotted lines.

The characteristic features of our design are shown by means of full lines in the drawings.

We claim:

The ornamental design for an airplane, substantially as shown and described.

EDWARD H. HEINEMANN.
LEO J. DEVLIN.
